UNITED STATES PATENT OFFICE.

EDWARD M. HEYLMAN, OF CANTON, ILLINOIS, ASSIGNOR TO THE PARLIN & ORENDOFF COMPANY, OF SAME PLACE.

CORN-PLANTER.

SPECIFICATION forming part of Letters Patent No. 574,539, dated January 5, 1897.

Application filed August 3, 1895. Serial No. 551115. (No model.)

To all whom it may concern

Be it known that I, EDWARD M. HEYLMAN, of Canton, in the county of Fulton and State of Illinois, have invented certain new and 5 useful Improvements in Corn-Planters, of which the following is a specification.

This invention relates to various details of a complete planter, all of which are capable of conjoint use. It is exemplified in the structure hereinafter described, and it is defined in the appended claims.

In the drawings forming part of this specification, Figure 1 is a plan of so much of a planter as is requisite to show the correlation 15 of the different features of the invention. Fig. 2 is an elevation of the wire-reeing mechanism, viewed from the right side of the planter. Fig. 3 is an enlarged detail representation of the friction-developing device of the reel.

20 Fig. 4 is a rear elevation of the reeling mechanism. Fig. 5 is an elevation of the left side of the reeling mechanism. Fig. 6 is an enlarged detail of the lock-bracket of the reel. Fig. 7 is an elevation of a seedbox and shank 25 with the check-row head removed and the check-row lever cut on sectional line X in Fig. 1. Fig. 8 is a detail of the check-row movement. Fig. 9 is a representation of the ratchet-wheel of the check-row movement. Fig. 10 30 illustrates the mechanism employed to actuate the second drop of the planter and shows in connection therewith a peculiar intermediate drop. Fig. 11 shows the same features as Fig. 10, but represents the second drop-valve open and the intermediate valve closed 35 instead of the reverse. Fig. 12 illustrates the manner in which the intermediate valve may be used to hold the second drop-valve open when the planter is used for drilling, and Fig.

40 Fig. 13 shows the intermediate valve in perspective and applied to such use. Fig. 14 is an elevation of the combined hand-and-foot drop, the elevation being taken on line Y in Fig. 1. Fig. 15 illustrates the reverse position of the mechanism shown in Fig. 14. Fig. 45 16 is a side view of the rear end of the tongue.

So far as this particular invention is concerned the general construction of the planter may be varied to a considerable extent apart 50 from the particular features claimed; but it

is preferably made substantially as shown in Fig. 1, where the axle is represented by 1; a wheel by 2; a side and end frame, formed of a continuous bar, by 3 and 3^a; a cross-bar, to which the side bars are hinged and which 55 carries the seedboxes, at 4; an intermittently-rotating drop-shaft at 5; seedboxes at 6; a tongue at 7; a lift-bar at 9; and other features, as indicated.

The lower surface of the rear end of the 60 tongue is rounded off, as shown at 7^a in Fig. 16, and a plate, as 13, with a reversely-rounded end 13^a, is fastened to the under side of the tongue. Between the tongue and the plate is placed a spring-bar 8, the rear end of which 65 extends beyond the end of the tongue and provides a point of connection for the links 10, (in Fig. 1,) which connect the spring-bar with lift-bar 9. The plate 13 is preferably cast with lugs 14, extended beyond the sides 70 of the tongue, a saddle 12 is placed on the upper surface of the tongue, a U-bolt is placed in the saddle, with its ends extended through the lugs of the plate, as shown at 11, and bolt 13^b is passed through the plate and through 75 a hole in the tongue. This mode of construction provides a stiff strong plate, which may be attached to the tongue without weakening either plate or tongue; but in the broadest sense of this feature of the invention it is only 80 necessary that the spring-bar shall be held between the tongue and the plate and that the rounded surfaces shall be provided. The spring-bar 8 supplies sufficient elasticity to make the connection between the wheel-frame 85 and the box-frame desirably yielding, and the rounded bearings strengthen the spring against sudden shocks or unusual stress.

The vertical support for the seat is in the form of an arch 28, which rises from side bars 90 3. Brackets 29 and 33 are secured one to the left leg and the other to the right leg of the arch-frame, and both are concaved in their upper surfaces to receive the journals of the shaft 31 of the reel-drum 32. Bracket 29 has 95 a transverse recess to admit a lock-pin, as shown in Fig. 6, where the recess is indicated by 30 and the lock-pin by 52. The pin when used extends through the recess of the bracket and through a coinciding hole in the reel- 100

shaft. Its function is to prevent the shaft from turning in its bearings, and its utility will hereinafter appear.

The reel consists of the drum 32, held between the flanged spider-heads 32^a by bolts 32^b, and the bearings of the heads are loose on the shaft. A friction-wheel 38 (in Fig. 3) is fixed on the reel-shaft adjacent to one of the reel-heads, and the periphery of the wheel is preferably V-shaped in cross-section. A bracket 36 is fastened to the reel-head adjacent to the friction-wheel and is provided with bearing-pins 37. A pair of semicircular clamps embrace the friction-wheel, such clamps being designated by 35. At one end of each of the clamp members is a hook 35^a, adapted to engage a bearing-pin of bracket 36, and at the opposite end is an extension 35^b, through which bolt 39 extends. The bolt is somewhat elongated. It is screw-threaded to receive nut 40, and spring 41 is interposed between the nut and an extension of a clamp member. A sprocket-pinion 27 is fixed on the reel-shaft, and a chain 26 connects the pinion with a sprocket-wheel 25 on axle 1. On the scraper-shaft 53 is loosely mounted a wire-guide 48, which has at its front end a wire-receiving eye 49. Back of the eye (when the guide is in a wire-receiving position) the guide extends in a regular curve backward and upward, and its under surface is concaved in cross-section to hold the wire against lateral displacement. The bearing of the guide on the scraper-shaft is elongated, as shown at 45 in Fig. 4, thereby facilitating a sliding motion of the guide lengthwise of the shaft, a lug 44 is formed on the side of the guide, a link 43 connects the lug with the lower end of lever 42, and the lever is pivoted on a pin 34, which projects from reel-bracket 33. Fingers 46 extend rearward from the bearing of the guide in position to strike the under surface of the rear cross-bar 3^a of the planter-frame, and their function is to coact with the wire in holding the guide in the position shown in Figs. 2 and 4. Stop extensions 47 project from the guide-bearing lengthwise of the scraper-bar, and by striking against the journal-brackets of the shaft prevent the guide from traveling past the ends of the reel.

In Figs. 2 and 4 the reel is represented in the act of taking up the wire automatically as the planter travels across the field, and preliminary to such operation the following acts have been performed: First, the wire, which is designated by 50, is threaded through the guide and attached to the reel; second, the wire is caught over the guide-hook 51, attached to the forward part of the planter-frame; third, the nut 40 is adjusted until the spring 41 exerts the proper pressure on the clamps to produce friction sufficient to wind the wire as fast as it is supplied and provide for slippage when the travel of the planter is slower than the winding speed of the reel, and, fourth, the pin 52, if in the locking position, (shown in Fig. 6,) must be withdrawn. Then

as the planter moves forward the reel-shaft is driven positively by the chain and the fixed wheels and the reel turns in the same direction with a force dependent on the amount of friction developed by the clamps on the friction-wheel. The natural speed of the reel, slippage not being considered, is more than sufficient to take up the wire as fast as the planter travels, and so the wire is wound with a degree of tightness depending on the adjustment of nut 40. As the planter moves forward the driver grasps lever 42 in his right hand and with a slow steady motion back and forth moves the guide from side to side and evenly distributes the wire on the reel.

In Fig. 5 the reel is represented in the act of laying out the wire, and preparatory to this operation the lock-pin has been placed in position to hold the reel-shaft from rotation and the tension of the friction device has possibly been loosened. The effect of the friction in this case is simply to impede the rotation of the reel on the shaft sufficiently to properly stretch the wire as it is laid out. In this figure the wire-guide, which is inoperative and therefore hanging loose from the scraper-shaft, is shown encountering an obstruction and swinging backward to pass over the same. This is a possibility incidental to the loose mounting of the guide on the round bar or shaft, and the utility thereof is obvious.

The utility of the fingers 46 of the guide depends on the relation of the scraper-shaft to the rear cross-bar of the frame, the shaft occupying a position below and somewhat in front of the bar.

The check-row head 54 is in this instance provided with a horizontally-swinging forked lever 55. The lever is connected with rod 56 through the intervention of a concaved saddle-block 57 and a hook-bolt or eyebolt 58. The block sits on the rod, with the end of the lever on the block. The bolt embraces the rod and passes through the block and lever, and when it is tightened it tends to bend the rod to an extent sufficient to make the connection secure and provide for very nice adjustment lengthwise of the rod.

The rod 56 connects the forked lever with arm 59, which is pivoted at its opposite end with some relatively-fixed part of the planter, in this instance a bracket depending from the seedbox 6. A drive-pawl 60 is pivoted on the arm between the ends thereof and its free end forked to an extent sufficient to engage the round bars 62 of ratchet-wheel 61 both top and bottom. The ratchet-wheel is fixed on the drop-actuating shaft 5, and it comprises the disk-wheel 61, the round bars 62, projecting from the face of the disk, and the ring 61^a on the extended ends of the bars. The pawl engages a bar of the wheel with its extension 60^a (in Fig. 8) under a portion of the same, and when a throw is made, as shown in Fig. 7, a positive stop is effected by the bar next following striking the under surface of the pawl. On account of the peculiar relation of the

pawl to the bar the front end of the pawl is held from rising as the throw is completed and its under surface lies in the path of the bar next following. The pawl acts between 5 the disk and the ring of the ratchet-wheel, which provide ample space, and on this account the pawl may be joined loosely to the arm and still keep accurately to its work.

A lift-ratchet wheel 76 is fixed on shaft 5 10 under the seedbox, and it tends to actuate a lever 63 of somewhat peculiar construction. The lever has an incline or tooth 64, adapted to the recesses of the lift-ratchet. It is pivoted at 65, it is annular at 66 to permit passage of corn, and it has at its free end eye 67 and hook 68. A rod 69 connects the lever with the second drop-valve 70, and as the lift-ratchet is turned the lever rises to open the second drop-valve and falls to close it. The 15 20 plate under the first drop-disk of the planter has a diminutive spout 71, and a valve 72 is swung from lugs 73 in position to close the spout. The free end of the intermediate valve 72 rests on the swinging end of lever 63, 25 and when the lever rises to open the second drop-valve it carries the intermediate valve against the spout and precludes the passage of corn until by a reverse motion the second drop-valve is closed. This prevents dribbling, 30 which may otherwise occur when a planter is moved unusually slow.

To adjust the intermediate valve accurately and to provide for compensation for wear, a set-bolt 74, adapted to bear against the lever 35 and provided with a jamb-nut, may extend through the valve, as shown.

When it is desired to use the planter for drilling, the second drop-valve may be held open by hooking end 68 of the lever 63 through 40 slot 72^a, Fig. 13, of valve 72, as shown in Figs. 12 and 13. To facilitate this use of the intermediate valve, the pin 75, which holds the valve in connection with lugs 73, is made easily removable, and the slot is of course so 45 located that the lever will be raised when the hook is therein.

A hand-lever that may be used independent of the check-row-wire mechanism by a boy seated on the planter is generally considered to be a necessary adjunct of a complete planter, and in some instances it is advantageous for the driver to actuate the drop with his foot. To provide a single device that will meet both of these requirements is the object 55 of the mechanism specifically illustrated in Figs. 14 and 15, and the details thereof are as follows: Ratchet-wheel 20 is the same as the wheel 61 of Fig. 9. Bracket 17 is journaled on casting 16, Fig. 1. Hand-lever 18 is fastened to bracket 17, on one side thereof. Pawl 19 is swung from the opposite side of the bracket, as is also connecting-bar 21. Casting 22 is secured to the planter-frame, and it provides a pivotal support for the foot-lever 23 60 and a housing for spring 24. The spring tends to hold the different parts in the positions shown in Fig. 14, and it retracts the pawl after

it is thrown to the position shown in Fig. 15, whether the operation be effected through the foot-lever or the hand-lever. The pawl is 70 hooked to correspond with the forked peculiarity ascribed to pawl 60. It bears against the ratchet-bars top and bottom, and it has an under surface at 19^b which acts as a stop at the completion of a throw by impeding the motion of the bar following the one with which the hook is engaged. The hooked part 19^a (seen only in Fig. 14) bears against the under surface of the bar and prevents the pawl from rising as the stop is made. 75

The housing 22 is cut away at its under side to receive the spring and permit motion of the foot-lever, and its extreme forward end forms a recess that retains the spring in position. 80

Having thus described my invention, I claim as new and desire to secure by Letters Patent—

1. A planter-tongue the under surface of which is rounded upward at its rear end, a 90 plate secured to the under side of the tongue and having the upper surface of its rear end rounded downward, a spring lift-bar held between the tongue and the plate and extended rearward thereof, and a stiff link connecting 95 the extended end of the spring-bar with the lift-lever of the planter, substantially as set forth.

2. A planter-tongue the under surface of which is rounded upward at its rear end, a 100 plate under the tongue having a downcurved rear end and side lugs, a saddle on the tongue, a U-bolt resting in the saddle and extending through the lugs, and a spring lift-bar held between the tongue and the plate and extended rearward thereof, substantially as set forth. 105

3. A reel for planters, comprising a reel-shaft adapted to be either driven from the planter or locked against rotation, and a reel 110 on the shaft connected therewith by a friction-clutch, or friction-developer, substantially as set forth.

4. In a planter, the combination of a reel journaled under the driver's seat, and a wire-guide mounted slidably on the scraper-bar, substantially as set forth. 115

5. In a planter, the combination of a round scraper-bar, or shaft, a wire-guide mounted loosely on the scraper-bar, and a reel journaled above the scraper-bar, substantially as set forth. 120

6. In a planter, the combination of the rear cross-bar of the frame, a scraper-bar below and slightly in front of the cross-bar, a wire-guide on the scraper-bar adapted to swing against the cross-bar, and a reel above the bars, substantially as set forth. 125

7. In a planter, the combination of a reel under the driver's seat, a wire-guide mounted 130 on the frame under the reel, and a lever, adjacent to the seat, connected with the wire-guide, substantially as set forth.

8. In a planter, the combination of a reel

under the driver's seat, a wire-guide mounted slidably on the frame under the reel, a lever, adjacent to the seat, connected with the wire-guide, and an auxiliary guide-hook extended 5 below the front or runner planter-frame, substantially as set forth.

9. A wire-guide for the reels of planters comprising a sleeve adapted to a scraper-bar, an eye portion, a curved and concaved portion, and stop-fingers adapted to engage a cross-bar of the planter, substantially as set forth.

10. A friction clutch, or developer, for check-row wire-reels, comprising a friction-wheel, a bracket secured to the reel and having pivot-pins, clamp members adapted to embrace the wheel and having hooks to engage the pivot-pins, a bolt extending through the free ends of the clamp members, a nut on 15 the bolt, and a spring between the nut and one of the clamp members, substantially as set forth.

11. An adjustable connection between a check-row lever and a connecting-rod, the 25 same consisting of a concaved saddle-block placed between the rod and the lever with the concaved face against the rod, and a hook, or eye, bolt embracing the rod and extending through the block and the lever, substantially 30 as set forth.

12. A check-row movement comprising a 35 forked lever, a rock-arm, a pawl having a forked operative end, and a ratchet-wheel the teeth of which are rod-formed, the forked lever being connected with the rock-arm and the pawl being pivoted on the rock-arm and adapted to engage the ratchet-teeth, substantially as set forth.

13. A check-row movement consisting of a ratchet-wheel composed of a disk, a ring and 40 interposed rods, a forked pawl adapted to engage the teeth of the ratchet, a rock-arm carrying the pawl, and a forked lever connected with the rock-arm, substantially as set forth.

14. The combination with an intermittently-oscillating lever situated under a seed-box and adapted to actuate the second drop-valve of a planter, of an intermediate swinging valve having its free end resting on the lever in position to close the passage from 50 the seed-disk when the lever rises, substantially as set forth.

15. The combination with an intermittently-oscillating lever situated under a seed-box and adapted to actuate the second drop-valve of a planter, of an intermediate swinging valve having its free end resting on the lever in position to close the passage from 55 the seed-disk when the lever rises, such intermediate valve being detachable from its pivot and having a recess adapted to engage the outer end of the lever and hold it raised, substantially as set forth.

16. The combination of a ratchet-wheel, a pawl adapted to intermittently actuate the 60 wheel, a hand-lever with which the pawl is connected, a foot-lever, a bar connecting the hand-lever with the foot-lever, and a retractile spring common to both the hand-lever and the foot-lever, substantially as set forth.

In testimony whereof I sign my name in the presence of two subscribing witnesses.

EDWARD M. HEYLMAN.
